UNITED STATES PATENT OFFICE.

ALFRED B. HUTCHINSON AND ERNST F. AUTENRIETH, OF BROOKLYN, NEW YORK, ASSIGNORS TO THE GLEN COVE MACHINE COMPANY, (LIMITED,) OF SAME PLACE.

WOOD-PLANING MACHINE.

SPECIFICATION forming part of Letters Patent No. 398,048, dated February 19, 1889.

Application filed January 30, 1888. Serial No. 262,396. (No model.)

To all whom it may concern:

Be it known that we, ALFRED B. HUTCHINSON and ERNST F. AUTENRIETH, both of Brooklyn, (Green Point,) in the county of Kings and State of New York, have invented a new and useful Improvement in Wood-Planing Machines, of which the following is a specification.

The invention will be hereinafter described, and particularly pointed out in the claims.

In the accompanying drawings, Figure 1 is a side elevation of a portion of a machine embodying our invention. Fig. 2 is a transverse section upon the plane indicated by the dotted line $z z$, Fig. 1. Fig. 3 is a transverse section of an upper roll-frame, whereby the two sections of an upper feed-roll are supported upon the plane indicated by the dotted line $x x$, Fig. 2.

Similar letters of reference designate corresponding parts in all the figures.

A designates the side frames of the machine, and B designates an upper cutter-head. The journals b of this cutter-head are fitted in boxes b' upon a cutter-head frame, B' , which has brackets or flanges b^2 , bearing upon the cutter-head stands A' , which rise from the main frame A. The cutter-head frame B' may be adjusted upward and downward upon the stands A' by any of the means usually employed for this purpose, and we have not shown such adjusting means, as our invention in nowise relates thereto. The cutter-head B is driven by a belt, b^3 , from a pulley on the usual counter-shaft, B^2 , which is at the front or feeding end of the machine. Upon the front side of the cutter-head B is a bar or mouth piece, B^3 , which extends across parallel with the cutter-head and which is adjustable in the cutter-head frame B' . Such adjustment may be accomplished by means of screws b^5 . Upon the opposite or rear side of the cutter-head B is a bar, B^4 , which constitutes a chip-breaker and which is adjustable upward and downward. This chip-breaker is supported from the cutter-head frame by means of arms or links b , which have circular eye portions c' embracing circular hubs concentric with the cutter-head

bearings B' . The ends of the chip-breaker are secured by screw-and-slot connection to the arms or links b .

Behind the cutter-head B we have represented two pairs of feed-rolls, which are upon the opposite sides of standards A^2 , rising from the main side frames, A. These standards A^2 have in them slots a , for a purpose herein-after described. The lower rolls, C, of the two pairs are journaled in stationary boxes c^5 , and the upper rolls, C' , are each composed of two sections, or, in shop parlance, are "broken," as best shown in Fig. 2. The sections of the upper rolls, C' , are mounted in boxes $c^6 c^7$, and the boxes of each of said upper rolls are supported in an upper roll-frame, C^2 , which extends transversely of the machine, as best shown in Fig. 2. The upper roll-frame, C^2 , has at opposite ends sockets or eyes c^8 , which fit rods $C^3 C^4$ at opposite sides of the machine.

The rods C^3 at the side of the machine opposite to that which is shown in Fig. 1 are simply smooth cylindric rods supported at their lower and upper ends in bearings or rests c^9 , and which serve simply as guides upon which the eyes or sockets c^8 at that end of the roll-frames C^2 slide. The rods C^4 at the side of the machine shown in Fig. 1 are screw-threaded, and the sockets or eyes c^8 which receive them are correspondingly screw-threaded and form nuts, so that by the turning of the screws C^4 the upper roll-frames C^2 , will be adjusted upward and downward. The screws C^4 are supported in lower bearings, c^{10} , and in upper bearings, c^{11} , upon the upright standards A^2 . The downward movement of these screws is prevented by collars c^{12} upon them resting upon their bearings c^{10} , but when the upper roll and its upper roll-frame, C^2 , are lifted, the corresponding screw C^4 is lifted. Each upper roll-frame, C^2 , is connected at opposite ends by rods d with arms d' upon a rock-shaft, D or D'. As here represented, both rock-shafts D and D' are concentric, the latter being tubular and journaled upon the former. The arms d' of one rock-shaft extend in one direction to the rods d , by which they are connected with one upper roll-frame, and the arms d' of the other

rock-shaft extend in the opposite direction to corresponding rods d , whereby they are connected with the other roll-frame. Consequently it will be understood that whenever either screw C^4 is turned by a handle, c^{13} , applied to its upper end both ends of the roll-frame C^2 will be raised equally, because of their connection with the one rock-shaft.

We do not claim as of our invention the combination, with the upper rolls of two pairs, of the two concentric rock-shafts, one surrounding the other, and which are connected by arms and rods, one with each of the upper roll-supports, as such subject-matter is included in the application of James F. Welch, Serial No. 262,109, filed January 27, 1888.

The lower ends of the screws C^4 are prolonged downward below their bearings c^{10} , and, as here shown, have connected with them a yoke, C^5 , and C^6 designates a weighted lever, which is fulcrumed at c^{11} , and which is hung by a stirrup, c^{15} , upon the yoke C^5 . This arrangement of weights being applied to the screws C^4 is, through the connection of each upper roll-frame, C^2 , at its opposite ends with one rock-shaft, distributed upon both ends of each upper roll-frame, C^2 .

The boxes c^6 c^7 in which the sections of each upper roll, C' , are journaled, have a limited vertical movement in the upper roll-frame, C^2 , and are loaded by springs. Each of the outer boxes, c^6 , is arranged in a slideway, e , and has bearing upon it a spring, e' , which is in a cup-shaped cavity, e^5 , in the roll-frame, and is here shown as of india-rubber. Above the spring e' is an adjusting-screw, e^3 , and by setting this screw downward the spring e' may be caused to act with greater force upon the box c^6 . The center or inner boxes, c^7 , are supported in a slideway, c^8 , and are limited in their upward movement by stop-bolts o .

Above them is a spring, e^4 , which is arranged in a cup-shaped cavity, e^5 , in the upper roll-frame, C^2 , and which is controlled or adjusted by a screw, e^6 . Below the spring e^4 , which is here represented as a spiral spring of steel, is a follower or plate, e^7 , and through a toggle-link, e^8 , and a saddle-piece, e^9 , the force of the spring e^4 is distributed upon the two inner roll-frame boxes, c^7 , which are at the adjacent inner ends of the sections of the upper roll, C' , as shown in Fig. 2. The link or knuckle e^8 has rounded or knuckle-shaped bearings upon both the disk or follower e^7 and the saddle-piece e^9 , and consequently the force of the spring e^4 is applied equally to both the adjacent boxes c^7 , and either box may rise to the extent permitted in the frame C^2 without disturbing or causing the other box to rise. The movement which the boxes c^6 c^7 have in the upper roll-frame is very limited, and need be only about one-quarter or three-eighths of an inch. When the boxes c^6 c^7 are maintained in their lowermost position in the frame C^2 , it is true that the weights which are applied to the roll-frame C^2 have no direct effect upon the boxes; but the springs e^2 e^4 with

which said boxes are loaded are of sufficient force to press the roll-sections C' into feeding contact with the lumber. When a wide piece 70 of lumber having an unequal thickness at its opposite edges is fed in, the roll-section C' upon the thicker side may rise and the companion section C' , instead of being raised therewith, will bear upon the lumber of least 75 thickness, and will therefore feed it straight through the machine; also, when two boards or pieces of slightly unequal thickness are fed in, the one roll-section C' may rise by its contact with the thicker lumber, while the 80 companion section C' may bear upon the thinner board or lumber and feed it properly along.

Upon the lower rolls, C , are pinions f , which are geared together by an intermediate wheel, 85 f' , and upon one of the lower rolls, C , is also a larger gear-wheel, f^2 , which is in gear with a driving pinion, f^3 , which may be upon what is usually termed the "pinion-shaft" F of the machine. 90

Inasmuch as the upper rolls, C' , are broken, it is necessary to drive positively the two sections of each roll. We therefore provide a shaft, F' , intermediate between the two upper rolls, and which is supported in bearings 95 f^4 , extending inward from one of the upper roll-frames, C^2 . The shaft F' is received in the slots a , formed in the standards A^2 , and consequently it is free to rise and fall with the upper roll-frames, C^2 . Upon each of the 100 sections of each upper roll, C' , are pinions or wheels f^5 , both of which are in gear with corresponding pinions or wheels, f^6 , upon the intermediate shaft, F' , and consequently if rotary motion is transmitted to the shaft F' the 105 sections of both the upper rolls will be individually driven therefrom.

Upon one of the lower rolls, C , at its end opposite the connecting-gears f f' is a pinion, f^7 , and upon a corresponding end of the intermediate shaft, F' , is a wheel or pinion, f^8 . Gearing with both said wheels f^7 f^8 is an expansion gear or wheel, f^9 , which is supported by swinging links f^{10} from the shaft F' and from the lower roll, C , on which is the wheel 115 f^7 . Consequently, no matter what the rising or falling movements of the shaft F' and the upper rolls, motion is always transmitted through the wheels f^7 f^9 f^8 to the upper shaft, F' , and thence to the upper rolls. 120

We make no claim, broadly, to the arrangement and construction of the expansion-gear shown here to transmit motion to the upper roll or to the wheel or shaft geared with the upper rolls of two adjacent pairs, as such subject-matter is broadly claimed in the aforesaid application of James F. Welch; but we limit our use of such expansion-gear to its combination with upper rolls each composed of two sections and an intermediate shaft between the two upper rolls and which is geared with the sections of each roll. 125

What we claim as our invention, and desire to secure by Letters Patent, is— 130

1. The combination, with a lower feed-roll, journaled in stationary bearings, of an upper roll composed of two sections arranged end for end, an upper roll-frame in which both sections of the upper rolls are journaled at each of their ends, said frame comprising sockets at the ends thereof and made integral therewith, one of said sockets forming a nut, two vertical rods, one at each side of the machine, and one of which is a screw engaging said nut, a crank for rotating said screw so as to bodily raise and lower the roll-frame and the upper roll-sections journaled therein, journal-boxes for the upper roll-sections supported wholly in said frame and capable of a limited vertical movement therein, said journal-boxes being acted upon by springs to press them downwardly in the frame, substantially as specified.
2. The combination, with the lower roll, C, and the upper roll-sections, C', of the upper roll-frame, C², the boxes for the roll-sections having a limited vertical movement in said frame, the springs e', whereby the outer boxes are held down, and the springs e⁴, and a saddle whereby the two inner boxes are held down, substantially as herein described.
3. The combination, with two pairs of upper and lower rolls, the lower rolls being journaled in stationary bearings, and the upper rolls being each composed of two sections, of an upper roll-frame for the sections of each roll, and boxes for the roll-sections having a limited vertical movement in said frame, a shaft intermediate between the upper rolls and geared with the two sections of each upper roll, and journaled in bearings projecting from one of the roll-frames, gearing connecting the lower rolls of the two pairs, and expansion-gearing connecting one of said lower rolls with the said intermediate shaft, substantially as herein described.
4. The combination, with a lower feed-roll journaled in stationary bearings, of an upper feed-roll composed of two sections arranged end for end, an upper feed-roll frame in which both sections of the upper roll are journaled at each of their ends, said frame comprising sockets c⁸, made integral therewith and at the ends thereof, one of said sockets forming a nut, two vertical rods, one upon each side of the machine, extending through said sockets, one of said rods being a screw and engaging a screw-thread in its coating socket, a crank whereby said screw-rod may be moved up and down in order to bodily raise and lower the frame and the upper feed-roll section, a rock-shaft having arms connected by rods with the ends of said upper roll-frame, a weight applied to said rods, and boxes for the upper roll-section having a limited vertical movement in said frame, and which are acted upon by springs to press them down in the frame, substantially as specified.
